UNITED STATES PATENT OFFICE

1,964,534

AMUSEMENT DEVICE

Fred Schofer, Bronx, N. Y.

Application August 9, 1933, Serial No. 684,303

8 Claims. (Cl. 273—102)

This invention relates to a novel and improved amusement device for amusement parks, playgrounds, etc. and it is the principal object of my invention to provide a combination shooting gallery and ball game for the amusement of young and old in which bullets shot from stationary rifles, airguns etc., destroy easily breakable receptacles, having preferably the form of airplanes to free balls which, running down a ball guide into suitably marked pockets, close electric circuits in which lamps are located illuminating said pockets to indicate the winner of a shooting contest and the game combined therewith according to pre-arranged rules.

15 It will be evident that in place of airplanes I may use balloons, Zeppelins or any other suitable ball containers of easily destroyable material, such as thin rubber, celluloid, etc.

Another object of my invention is the provision 20 of a suitable frame or shelter for housing my device which may have the form of a stage presenting the silhouette of a city and its river front, or any desired landscape or view, whereby the river water may be represented as calm or choppy etc.

25 Still another object of my invention is the provision of a stage combined with a ball guide in form of an inclined board equipped with a plurality of nails or pins suitably spaced between which a ball relieved from its destroyable holder

30 may roll down into suitably marked pockets to indicate the winner of a shooting competition according to pre-arranged rules.

A further object of my invention is the provision 35 of means for slowly guiding the ball containing airplanes across the front of the stage to form a target to be shot at from stationary guns so arranged as to be directed towards the targets only.

A still further object of my invention is the 40 provision of a plurality of ball receiving pockets so arranged at the foot of the ball guide board as to close suitable light circuits upon the reception of a ball in said pockets, and equipped with means to interrupt the circuits upon the determination 45 of the winner and to collect the balls thereafter.

Other objects of my invention are the provision 50 of holder frames for the readily destroyable containers for the balls to be freed by a well directed shot destroying its container, said frames equipped with spring controlled clamps to hold the containers in said frames and allowing a ready exchange of the same or the introduction of new ball containers.

55 My invention includes also suitable motor op-

erated chains from which the ball containers are suspended in a plurality of members, so arranged as to present all a suitable target for shots directed at the same from shooting guns of suitable type.

These and other objects and advantages of my invention will become more fully known as the description thereof proceeds and will then be more specifically defined in the appended claims.

In the accompanying drawings forming a material part of this disclosure:

Fig. 1 is a front elevation of an amusement device constructed according to my invention.

Fig. 2 is a section on line 2—2 of Figure 1.

Fig. 3 is a top plan view of the device.

Fig. 4 is a side elevation of the representation 70 of an airplane used with my device.

Fig. 5 is a fragmentary front elevation thereof.

Fig. 6 is an enlarged sectional view of an airplane used in connection with my device, the 75 section being taken on line 6—6 of Figure 5.

Fig. 7 is a fragmentary detail view of a clamp frame for the airplane holder.

Fig. 8 is a sectional detail view of a circuit closing device, the section being taken on line 80 8—8 of Figure 9.

Fig. 9 is a sectional front elevation of the circuit closer.

Fig. 10 is a circuit diagram.

As illustrated, the amusement device constructed according to my invention comprises a frame, stage or housing formed by the rear wall 10, front wall 11 having a show window 12 and an inner inclined shelf 13 and top 14, intermediate its ends. The shelf 13 carries on its underside at the front thereof an abutment 15 against which leans or rests the upper end of an inclined board 16 the lower end of which is resting against a beam 17.

The upper face of board 16 is provided with 95 a plurality of pins 18 forming ball guides, and above the same a plurality of cleats 19 varying in length are arranged in parallel relation spaced from one another to form ball guides or channels 20.

The lower end of board 16 carries a plurality of 100 juxtaposed ball receiving pockets 21 acting as circuit closers generally designated 22 and to be more fully described hereinafter.

A pane of glass or other transparent material 105 23 bearing numerals 24 at certain intervals and in any desired arrangement, is supported at intervals on its rear by spaced feet 25 forming suitable ball pockets, while the front part of the 110

pane is embedded into and held in the material of the front foot part 26 of the housing.

In the foot part a ball receiving chamber 27 is formed, illuminated by a plurality of lamps 28.

5 The inclined bottom wall 29 allowing the balls received in the chamber 27 to roll into a chute 30 inclined towards the rear to be delivered therein for further use.

10 A resetting device for the circuit pocket 21 at the end of each play comprising a wire 31 having a plurality of substantially square operating members 32 is arranged in rear of the open mouth of pocket 27 and is adapted to be operated by a draw rod 33 guided to the rear of housing 10 15 and provided with a handle 34.

On the stage in front of the rear wall 10 are displayed various buildings 35, landscapes, or for instance the silhouette of the city of New York, Chicago, etc. etc. and the upper face of board 13 20 may represent water and can be also so constructed as to represent waves etc.

The stage is illuminated by a plurality of lamps 36 arranged at the inner face of the front wall 11.

25 The top 14 carries near its ends sprocket wheels 37, 38 about which a chain 39 is guided from which depend at certain intervals the suspension wires or cables 40 for the horizontal bars 41 from each of which a plurality of wires 42 are suspended carrying at their lower ends the airplanes 43 or similar bodies, balloons etc. adapted 30 to be slowly moved in their consecutive order across the front of the stage.

35 The shaft 44 for sprocket wheel 38 carries a pulley 45 over which a belt 46 is guided, which is also guided over a pulley 47 on a spindle 48, which carries also a worm wheel 49 in mesh with a worm shaft 50, carrying a pulley 51 adapted to be operated by means of a chain or belt 52 from a suitable motor 53 in rear of the rear wall 11 of the housing or stage.

40 The airplanes 43, as shown in Figures 4 to 7, are composed of an easily destroyable material as for instance thin rubber, celluloid etc. adapted to be held in a frame composed of a rear or rudder part 57, upper cover 58 provided with the 45 wings 59, cabin 60 suspended from cables 42 and cockpit 61 adapted to hold a ball 62 resting upon the upper face of the destroyable body 43. In order to hold the body 43 to the suspension frame, lateral clamping frames 63, Figure 7, are provided having their clamping members held in engagement with the sides of the airplanes 43 by 50 means of springs 64 wound about the holder pins 65 held in brackets 66 of the frame.

45 In Figures 8 and 9, I have illustrated in detail the ball receiving pockets 21 and circuit closers 22. The pockets 21 are made of insulating material part of the upper edge of which is provided with a substantially semi-circular metal mounting 67 combined with a plate 67' connected by a wire 68 to one pole of a source of electricity. The metal cover 22 for pocket 21 is hinged there- 55 to by means of its pintle 69 connected by a wire 70 to the other pole of the source of electricity, and the cover has formed therewith a hook 71.

60 My device is used as follows:

From suitable stationary rifles, suitably arranged in front of the stage in such manner as to be directed onto the targets which are suspended from the chains and slowly passed in front of the stage, shots are fired and aimed to destroy one or the other of the destroyable airplane bodies to free the balls 62 held in their frames. Upon the scoring of a hit, the respective ball 62 will fall down into one of the channels 20 on board 16

and roll down the inclined surface thereof between the guide nails or pins 18 directing the ball into one of the pockets 21 to strike the hook 71 as indicated in Figure 8, turning the same about its pintle 69 to bring metal plate or cover 22 into engagement with the metal half-ring 67 to close a circuit in which the lamps 28 are located which will be illuminated so that the pocket in which the ball has been received will become visible through the numbered glass plate 23, and will remain so until the prizes have been determined, whereupon the operation of pull rod 33 and wires 31, 32 will move hook 71 to open cover 22 of each pocket and interrupt the circuit. The balls will run down the inclined bottom 29 of chamber 27 into chute 30 to be collected at the rear.

80 It will be understood that I have disclosed the preferred form of my invention only as one example of the many possible ways to practically construct the same, and that I may make such changes in the general arrangement thereof and in the construction of its minor details as come within the scope of the appended claims without departure from the spirit of my invention and 85 the principles involved.

90 Having thus described my invention, what I claim as new and desire to secure by Letters Patent is:

95 1. An amusement device comprising a stage, a plurality of readily destroyable targets suspended to move across the stage, balls normally held in said targets to be released upon the destruction of said targets by shots, a ball guide receiving and guiding the balls released from said targets, ball-receiving pockets, and means to close light circuits to illuminate the pocket upon the reception of a ball therein, means to visibly indicate a ball containing pocket, means to release the balls from their pockets and to open the circuit upon the termination of a game, and means 100 to collect the balls at the rear of the stage.

105 2. An amusement device comprising a stage, a plurality of easily destroyable targets, frames for removably holding said targets, means for suspending said targets in front of said stage, means to move said targets successively across the stage, balls held in said frames on said 110 destroyable targets to be released upon the destruction of the targets by a shot, a game board provided with means for guiding the ball released from the target through a devious path, pockets for receiving the ball from said board, pockets for the reception of a ball from said board, means combined with said pockets to close a light circuit upon the reception of a ball in one of said 115 pockets, means to visibly indicate the pocket in which a ball has been received, means to release the balls from their pockets and to open the light circuit again at the close of a game and 120 means for guiding the released balls to the rear of the stage.

125 3. In an amusement device of the character described, a housing having the form of a stage, the silhouette of a city forming the background, and the representation of a river forming the front part of the stage, destroyable targets, slowly moved across the stage containing balls to be 130 released upon the destruction of the target by a shot, and a game board for receiving and guiding said released balls into pockets provided with means to visibly indicate a pocket into which a ball has been guided.

135 4. In an amusement device of the character described, a housing having the form of a stage, 140

- a motor operated chain guided over sprocket wheels on top of the housing, frames suspended from said chain in suitably arranged groups, destroyable targets held in said frames containing 5 each a ball adapted to be dropped upon the destruction of said target by a shot, and a game board for receiving and guiding said released ball into pockets equipped with means for visibly indicating the presence of a ball in one of said 10 pockets. 80
5. In an amusement device of the class described, a housing having the form of a stage, a motor operated chain, frames suspended from said chain and guided on top of said housing to 15 successively appear in front of said stage, destroyable targets in form of airplanes held in said frames in suitable groups of three each, balls held in said frames upon said targets to be readily released upon the destruction of said target by a 20 shot, an inclined shelf upon which the released ball drops, a game board provided with ball guides to receive the ball from said inclined shelf to guide the same into pockets provided with circuit closing means operated by the ball dropping into the pocket to visibly indicate the pocket having 25 received a ball. 85
6. In an amusement device of the class described a ball guide and game board, a plurality of ball receiving pockets of insulating material at the lower end of said game board, a metal cover 30 for each pocket hinged by a pintle to said pocket, said pintle connected to one pole of a source of electricity, a metal mounting in form of a semi-circular ring connected to the other pole of said source of electricity, and a hook combined with said cover adapted to be engaged by a ball dropping into said pocket to swing the cover into engagement with the semi-circular ring to close the circuit, and means engaging said hook to manually open the pocket cover for releasing the ball and opening the circuit. 90
7. In an amusement device of the character described, a plurality of frames, easily destroyable targets held in said frames, balls held in said frames against said targets to be released upon the destruction of said targets means to suspend said frames and targets, and means for clamping said targets to said frames. 95
8. In an amusement device of the class described, a plurality of frames, destroyable targets held in said frames each frame having the form of an airplane including its tail end, cabin and cockpit, said cockpit adapted to receive and hold a ball resting on said destroyable target, means for suspending said frames, and spring controlled lateral clamps combined with said frames to engage laterally said targets and allow the introduction of new targets into said frame upon the destruction of the targets. 100
